(57) **CLAIM**

The ornamental design for a rocket bottle, as shown and described.

DESCRIPTION

FIG. 1 depicts an ornamental rocket bottle as seen assembled from the top.

FIG. 2 depicts the ornamental rocket bottle as seen assembled from the side.

FIG. 3 depicts the ornamental rocket bottle as seen assembled from the bottom; and,

FIG. 4 depicts the ornamental rocket bottle disassembled into a nose, cap and bottle body as seen from the side.

The broken line showing is for illustrative purposes only, and forms no part of the claimed design.
